(57) CLAIM

The ornamental design for a lounge chair, as shown and described.

DESCRIPTION

FIG. 1 is a front view of a lounge chair showing my new design;

FIG. 2 is a rear view of the lounge chair of FIG. 1;

FIG. 3 is a left side view of the lounge chair of FIG. 1;

FIG. 4 is a right side view of the lounge chair of FIG. 1;

FIG. 5 is a top view of the lounge chair of FIG. 1;

1 Claim, 7 Drawing Sheets
